UNITED STATES PATENT OFFICE.

JOHN P. HOFFMAN, OF ALBANY, NEW YORK.

TOOTH-BRUSH.

1,128,139.

Specification of Letters Patent.

Patented Feb. 9, 1915.

Application filed October 31, 1913. Serial No. 798,498.

To all whom it may concern:

Be it known that I, JOHN P. HOFFMAN, a citizen of the United States, residing at Albany, in the county of Albany and State 5 of New York, have invented certain new and useful Improvements in Tooth-Brushes, of which the following is a specification.

This invention relates to tooth brushes, and the principal object of the invention is 10 to provide a brush which will polish as well as clean the teeth.

Another object of the invention is to provide an improved type of polishing blocks which are so constructed that the polishing 15 powder will be prevented from being quickly removed from the blocks while brushing the teeth.

Another object of the invention is to so construct the brush that the cleaning bristles 20 will thoroughly clean the teeth and the polishing blocks polish them at the same time.

This invention is illustrated in the accompanying drawings wherein—

25 Figure 1 is a plan view of the improved brush; Fig. 2 is an elevation of the brush with the handle partially broken away to show the manner of connecting the handle with the head; Fig. 3 is a fragmentary sectional view showing the manner of mounting the blocks.

The head 10 of the brush is curved longitudinally, as shown in Fig. 2, and is provided with a neck 11 which is removably 35 connected with the handle 12 by means of a threaded stem 13 screwed into the socket 14 formed in the handle. By this construction a valuable handle, such as silver or any other substance, can be provided, and brush 40 heads formed of bone or any other suitable material removably connected with the handle.

A plurality of rows of bristles 15 are secured in the brush head 10 and extend diagonally across the head as shown in Fig. 1 so that the bristles will be so positioned 45 that they will operate very effectively upon the teeth and clean the same. Blocks 16 which are formed of rubber or some other 50 soft material such as leather or the like are carried by the head between the rows of bristles with their inner end portions fitting into sockets 17 formed in the head. This manner of mounting the blocks is

clearly illustrated in Fig. 3. These blocks 55 have their side edges cut diagonally to extend parallel with the rows of bristles as shown in Fig. 1 and are provided upon their outer faces with grooves 18 to hold the powder which is placed upon the brush. These 60 grooves 18 may extend diagonally across the brush head as shown in Fig. 1 so that the ribs formed by the grooves will travel diagonally across the teeth with a scraping motion thus causing the teeth to be very thoroughly 65 polished.

From an inspection of Fig. 2 it will be readily seen that the bristles 15 extend beyond the outer faces of the blocks 16 and that therefore the bristles will thoroughly 70 clean the teeth while the blocks are polishing the same. By having the blocks provided with the grooves the powder will lodge in these grooves and will therefore not be immediately scraped from the blocks 75 when the brush is in use. The head 10 is curved as shown in Fig. 2 so that the brush will fit easily in the mouth and conform to the contour of the teeth.

A brush has therefore been provided 80 which serves the double purpose of cleaning and polishing the teeth and which is so constructed that the teeth will be thoroughly cleaned and polished by the same operation. It may also be noted that the brush 85 is so constructed that it will fit easily in the mouth and one in which the head can be removed from the more valuable handle and thrown away when the bristles and block become worn out. 90

What is claimed is:

In a brush of the character described a head, rows of bristles extending diagonally across said head, polishing blocks carried by said head between said rows of bristles, 95 said blocks having their side faces extending parallel to said rows of bristles and provided upon their outer faces with grooves extending parallel to said bristles, said bristles extending beyond the outer faces of said 100 polishing blocks, and said blocks being set in pockets in the brush head.

In testimony whereof I affix my signature in presence of two witnesses.

JOHN P. HOFFMAN.

Witnesses:

FREDERICK W. TIETZ,
MARGARET TIETZ.
